GROUTING TOOL

Thomas P. Lenahan, Billie Jack Bradley, and Allen H. Limbaugh, Duncan, Okla., assignors to Halliburton Company, Duncan, Okla., a corporation of Delaware
Filed June 22, 1961, Ser. No. 118,850
7 Claims. (Cl. 175—235)

This invention relates to a method and apparatus for grouting unconsolidated formations and, more particularly, to a method and apparatus for drilling a hole and injecting grouting material to consolidate the soil around the drill hole.

One method for improving the load bearing characteristics of subsoil containing substantial quantities of sand, clay or gravel is to permeate the subsoil with grout to form a large, solid mass which is capable of withstanding heavy loads. The large mass of consolidated soil also prevents lateral slippage, for example, on hillsides.

The usual method of grouting is to drive a pipe into the soil by pumping water down through the pipe and out through a nozzle mounted on the end of the pipe. The stream of water issuing from the nozzle washes away the earth and the pipe falls downward into the resulting cavity. When the bottom of the pipe has reached the desired depth, the flow of water is stopped and grouting material is then pumped through the pipe and out at the bottom, permeating the surrounding soil. When it has hardened, the consolidated earth forms a foundation which has increased bearing strength and is resistant to lateral slippage.

The grouting tools heretofore proposed have several limitations. Since all of the grouting material must be forced through the jet at the bottom of the pipe, it takes a considerable amount of time to inject the grouting material into the bore hole. The penetration and distribution of the grouting material, also, is extremely limited since it is injected at a single point.

Attempts have been made to improve the distribution of grout in the drill hole by using compound pipe. The inner pipe conducts water for drilling and the outer pipe, which is provided with holes along its length, distributes grouting material. This method is not practical, however, since compound pipe is heavy and expensive.

Accordingly, it is an object of this invention to provide a method and apparatus for uniformly distributing grout in a bore hole.

It is a further object of this invention to provide a grouting tool which permits the rapid injection of grout in a bore hole.

Another object of this invention is to provide a grouting tool which is adapted to be mounted on standard drill pipe.

In accordance with a preferred embodiment of this invention, the grouting tool has a casing which is secured to a length of pipe. A nozzle is secured to the bottom of the casing and longitudinal slots are provided around the circumference of the casing above the nozzle. A screen is mounted on the inside of the pipe adjacent to the slots. A removable tube is mounted within the casing to block the flow of fluid through the slots in the casing. The tool is held in a vertical position and water is pumped through the nozzle to drill a hole for the pipe. When the desired depth is reached, the flow of water is stopped and a sinker bar with a snap ring on its nose is run down the pipe to retrieve the tube. The upper end of the tube is provided with an interior flange which is engaged by the snap ring to facilitate removal of the tube. A ball is then dropped into the pipe to rest on a seat above the nozzle to prevent grouting material from flowing out through the nozzle. When the grouting material is

2

pumped into the pipe it flows outward through the screen and longitudinal slots. This permits a higher rate of flow of the grouting material than is possible through the jet and results in a larger distribution of the grouting material along the length of the bore hole.

This preferred embodiment of the invention is illustrated in the accompanying drawings, in which:

FIGURE 1 is an elevational view of a grouting tool suspended in a bore hole.

FIGURE 2 is a cross sectional view of the grouting tool.

FIGURE 3 is a cross sectional view of the lower portion of the grouting tool showing the tool during a drilling operation.

FIGURE 4 is a cross sectional view of the upper portion of the grouting tool showing a sinker bar and snap ring in engagement with the tube.

FIGURE 5 is a cross sectional view of the grouting tool showing the tool during grouting.

20 In accordance with a preferred embodiment of the invention, referring to FIGURES 1 and 2, a casing 1 is threadably secured to a well pipe 2 by means of a connector 3. The casing 1 is provided with a plurality of longitudinal slots 4 spaced around the circumference of the pipe. A tubular screen 5 is secured to the interior of the casing and extends along the length of the slots 4. The screen 5 is a composite, water-well type screen with a layer of heavy mesh screen adjacent the slots and a layer of fine mesh screen adjacent the interior of the casing 1. The mesh of the screen is sufficiently fine to prevent sand or soil from the well bore from entering the casing 1, but not fine enough to prevent the flow of grout outward through the screen 5.

35 A valve body 6 is threadably secured to the lower end of the casing 1. The valve body 6 is provided with a central bore 7 which communicates with the interior of the casing 1. An enlarged portion of the bore 7 forms a seat 8 for a tube 9 which is telescoped within the casing 1 and connector 3. The tube 9 has substantially the same outer diameter as the inner diameter of the connector 3. O-rings 10 and 11 mounted on the tube 9 cooperate with the connector 3 and valve body 6, respectively, to form a seal to prevent the flow of fluid into the space between the interior of the casing 1 and the outside of the tube 9.

40 A nozzle 12 is threadably secured to the lower end of the valve body 6. The interior of the nozzle 12 and the lower portion of the valve body 6 form a cage for a ball check valve assembly 13. Referring to FIGURES 2 and 5, a base 14 having a pair of supporting legs is mounted on a flange 15 on the interior of the nozzle 12. A tube 16, having longitudinal slots 17, is slidably attached to the base 14 by the legs of the base which extend through the slots 17 in the tube. A ball 18 is secured to the opposite end of the tube 16 and a spring 19, which is confined within the tube 16, exerts a force on the base 14 to urge the ball against a seat 20 in the valve body 6. The spring closes the valve 13 to prevent fluid from flowing back into the casing 1 through the nozzle 12 when there is no drill fluid flowing through the bore 7. The lower end of the nozzle 12 is provided with an orifice 21 to permit fluid to flow out through the end of the pipe.

55 The interior of the tube 9 is provided with a cylindrical recess portion 22 of an enlarged diameter. The top of the cylindrical recess portion 22 forms an internal flange 23. The interior of the tube 9 is sufficiently large to permit a sinker bar 24 to be inserted into the tube, as shown in FIGURE 4. The sinker bar 24 is provided with a snap ring 25. The snap ring is compressed by a tapered portion 26 at the top of the tube 9 and the snap ring 25 expands when it enters the cylindrical recess portion 22. As the sinker bar 24 is raised, the snap ring 25 engages

the flange 23 on the tube 9, and lifts the tube 9 upward through the pipe 2.

Before injecting the grouting material into the bore, it is necessary to block the bore 7. This is accomplished, as shown in FIGURE 5, by dropping a ball 27 down through the pipe 2. The ball is large enough to become lodged on the seat 8 of the valve body 6, thereby acting as a valve to prevent grout from flowing out through the bore 7.

In operation, the tool is assembled as shown in FIGURE 2 and a hose 28 is attached to the top of the pipe 2. Water, or other drill fluid, is pumped through a hose 28, into the pipe 2 and through the casing 1. The pressure of the water on the ball 18 causes the check valve 13 to open, permitting the water to flow through the nozzle 12 and out of the bottom of the pipe through the orifice 21. The stream of water issuing from the nozzle 12 washes away the soil at the bottom of the hole, forces it up along the sides of the casing 1 and out at the top of the hole, as shown in FIGURE 1. The screens 5 prevent sand from entering the casing and from becoming packed around the tube 9. An accumulation of sand or debris between the casing 1 and the tube 9 is undesirable, since it might form an obstruction to the removal of the tube 9. At this time there is no flow of water through the slots 4 since O-rings 10 and 11 on the tube 9 seal the slots 4 from the interior of the casing 1.

When the desired depth has been reached, the water is shut off and due to the drop in water pressure the check valve 13 closes. A sinker bar 24 with a snap ring on its nose is run down the pipe 2 to retrieve the tube 9. After the tube is removed from the pipe, a ball 27 is dropped down the pipe. The ball lodges on the seat 8 of the valve body 6 to prevent the flow of grouting material through the bore 7 of the valve body. The grouting material is then injected into the pipe and flows outward through the screens 5 and the slots 4 in the side of the casing 1. The valve 13 prevents the return flow of the grouting material into the casing through the nozzle 12.

After the grout has been injected in the well bore, the pipe can be removed from the well and reused, or it can remain in the well supported by the consolidated subsoil. Since the exterior surface of the grouting tool does not have any projections which would resist the removal of the tool, it can be easily raised from the well bore immediately after the grout has been applied.

There are several advantages in pumping the grouting material through the slots in the side of the pipe 1 rather than through the nozzle 12. One important advantage is that the flow area through the screen is much greater than through the nozzle and the grouting material can be injected much more rapidly. Another advantage is that the large area of application will result in a more even distribution of grouting material in the well bore.

The grouting tool of this invention is adapted to be used with standard well pipe. The depth of the well is not limited to the length of the grouting tool and therefore grouting material can be applied at a variety of depths with the same tool. The tool of this invention permits the use of a single conduit for supplying a high pressure stream of fluid for drilling and injecting grout over a large area, sequentially.

While the invention has been illustrated and described in one embodiment, it is recognized that variations and changes may be made therein without departing from the invention as set forth in the claims.

We claim:

1. Apparatus for drilling wells and for injecting grouting materials into unconsolidated subsoil formations comprising a casing, means for securing the casing to the end of a conduit, said casing having apertures in the wall thereof, a nozzle secured to the end of the casing for directing a stream of fluid downwardly to erode the soil beneath the pipe, valve means in the nozzle, a tube

telescoped within the casing in fluid sealing relation across said apertures, means for removing the tube, and means for shutting off outward flow of fluid through the nozzle when the tube is removed.

2. Apparatus for drilling wells and for injecting grouting materials into unconsolidated subsoil formations comprising a casing, means for securing the casing to the end of a conduit, said casing having longitudinal slots extending through the wall thereof, a screen secured to the inside of the casing over the slots, a nozzle secured to the end of the casing for directing a stream of fluid downwardly to erode the soil beneath the pipe, a sleeve valve mounted in the casing for preventing flow of fluid through the slots, a check valve in the nozzle for preventing reverse flow of fluid from the nozzle to the casing and means for opening the sleeve valve.

3. Apparatus for drilling wells and for injecting grouting materials into unconsolidated subsoil formations comprising a casing, means for securing said casing to the end of a conduit, said casing having longitudinal slots extending through the wall thereof, a screen secured to the inside of the casing over the slots, a nozzle secured to the end of the casing for directing a stream of fluid downwardly to erode the soil beneath the pipe, a sleeve valve mounted in the casing for preventing flow of fluid through the slots, said casing having a valve seat therein for engagement by the sleeve valve, a check valve in the nozzle for preventing reverse flow of fluid from the nozzle to the casing and means for opening the sleeve valve.

4. Apparatus for drilling wells and for injecting grouting materials into unconsolidated subsoil formations comprising a casing, means for securing said casing to the end of a conduit, said casing having longitudinal slots extending through the wall thereof, a screen secured to the inside of the casing over the slots, a nozzle secured to the end of the casing for directing a stream of fluid downwardly to erode the soil beneath the pipe, a sleeve valve mounted in the casing for preventing flow of fluid through the slots, a check valve in the nozzle for preventing reverse flow of fluid from the nozzle to the casing, means for opening the sleeve valve and means for selectively blocking flow of fluid from the casing through the nozzle whereby after the sleeve is opened, fluid is directed from the casing through the slots.

5. Apparatus for drilling wells and for injecting grouting materials into unconsolidated subsoil formations comprising a casing, means for securing said casing to the end of a conduit, said casing having longitudinal slots extending through the wall thereof, a screen secured to the inside of the casing over the slots, a nozzle secured to the end of the casing for directing a stream of fluid downwardly to erode the soil beneath the pipe, said casing having a valve seat therein, a tube telescoped in the casing and extending along the slots, sealing means between the tube and the casing for preventing fluid flow from the casing through the slots, said tube engaging the valve seat, a check valve in the nozzle for preventing reverse flow of fluid from the nozzle to the casing and means for removing the tube from the casing.

6. Apparatus for drilling wells and for injecting grouting materials into unconsolidated subsoil formations comprising a casing, means for securing said casing to the end of a conduit, said casing having longitudinal slots extending through the wall thereof, a screen secured to the inside of the casing over the slots, a nozzle secured to the end of the casing for directing a stream of fluid downwardly to erode the soil beneath the pipe, said casing having a valve seat therein, a tube telescoped in the casing and extending along the slots, sealing means between the tube and the casing for preventing fluid flow from the casing through the slots, said tube engaging the valve seat, a check valve in the nozzle for preventing reverse flow of fluid from the nozzle to the casing, means for removing the tube from the casing and a plug co-

operating with the valve seat to block the flow of fluid from the casing through the nozzle after the tube is removed.

7. Apparatus for drilling wells and for injecting grouting materials into unconsolidated subsoil formations comprising a casing, means for securing the casing to the end of a conduit, said casing having apertures in the wall thereof, a nozzle secured to the end of the casing for directing a stream of fluid downwardly to erode the soil beneath the pipe, one-way valve means for allowing fluid flow out of the nozzle, but preventing fluid flow into the casing through the nozzle, means extending across the apertures in fluid sealing relation with the casing, means for selectively removing the sealing means to permit fluid flow through the apertures, and means for

shutting off outward flow of fluid through the nozzle after the sealing means is removed.
